CIRCUIT BREAKER

John W. May, Pittsburgh, Pa., assignor to Westinghouse Electric & Manufacturing Company, East Pittsburgh, Pa., a corporation of Pennsylvania

Application December 26, 1941, Serial No. 424,421

24 Claims. (Cl. 200—88)

This invention relates to circuit breakers and more particularly to circuit breakers of the type which are tripped instantaneously in response to overload currents above a predetermined value and after a time delay on lesser overloads.

It is an object of the invention to provide a circuit breaker with an improved trip device of simple and inexpensive construction, which is operable to trip the breaker instantaneously in response to overload currents above a predetermined value and after a time delay for persistent overloads below said predetermined value.

Another object of the invention is the provision of a circuit breaker having an improved trip device comprising an electromagnetic tripping means which is operable to trip the breaker instantaneously upon the occurrence of overloads above a predetermined value, and a current responsive thermal trip element which is operable after a time delay in response to overloads below said predetermined value to cause the electromagnetic trip means to trip the breaker.

Another object of the invention is the provision of a circuit breaker having an improved tripping mechanism comprising an electromagnetic means energized by the current of the circuit for moving a trip member to trip the breaker, a biasing spring releasably connected to the trip member for opposing operation thereof, and a current responsive thermal element operable when heated a predetermined amount by overload current to release the trip member from the biasing spring to permit operation of the trip member by the electromagnetic means, the electromagnetic means being operable in response to overloads above a predetermined magnitude to operate the trip member instantaneously irrespective of the opposing force of the spring.

Another object of the invention is the provision of a circuit breaker as described in the preceding paragraph, wherein the spring which opposes movement of the trip member remains connected thereto during the entire operation of the trip member by the electromagnetic means upon overloads above the predetermined magnitude.

Another object of the invention is the provision of a circuit breaker having an improved tripping mechanism including a thermally responsive trip element, the construction being such that only a very light force is required to be exerted by the thermally responsive trip element to cause a tripping operation of the breaker.

Another object of the invention is to provide a circuit breaker with a trip member which is

biased to normal position by a spring connected thereto by a latch member which is releasable at times to disconnect the trip member from the spring, and a bimetal element operable when heated a predetermined amount in response to overload currents to unlatch the trip member from the spring.

A further object of the invention is to provide a circuit breaker with a novel trip device in which a bimetal element acts when heated a predetermined amount to disconnect a trip member from a spring biasing means which opposes tripping operation thereof, the trip member being operable on overloads above a predetermined value without disconnecting the biasing means and operable in response to overloads below said value only when disconnected from the spring biasing means.

Another object of the invention is the provision of a circuit breaker having a thermally responsive trip element and an improved means for adjusting the operating characteristic of the thermal trip element by varying the force of a spring engageable with the trip element.

Another object of the invention is the provision of a circuit breaker having a current responsive bimetal trip element and improved means for adjusting the operating characteristic of the bimetal trip element and for compensating said element for changes in ambient temperature.

Another object of the invention is the provision of a circuit breaker having a current responsive bimetal trip element and an ambient temperature compensating bimetal element connected thereto by a spring means, and manually operable means for adjusting the position of the compensating bimetal element to adjust the operating characteristic of the current responsive bimetal element.

The novel features that are considered characteristic of the invention are set forth in particular in the appended claims, the invention itself, however, both as to structure and operation, together with additional objects and advantages thereof, will be best understood from the following detailed description of several embodiments thereof when read in conjunction with the accompanying drawings, in which:

50 Figure 1 is a vertical sectional view of a circuit breaker embodying the principles of the invention, the breaker being shown in the closed circuit position;

55 Fig. 2 is a fragmentary sectional view at an enlarged scale taken substantially along the line

II—II of Fig. 1 and looking in the direction of the arrows;

Fig. 3 is an enlarged detail sectional view through the trip device taken substantially on line III—III of Fig. 2 and showing the position of the parts when the trip member is operated by the electromagnet after release from the spring means by the bimetal element;

Fig. 4 is a sectional view similar to Fig. 3 showing the position of the parts when the trip member is operated by the electromagnet without having been released from the spring means;

Fig. 5 illustrates a modification of the invention and represents a sectional view taken on line V—V of Fig. 6;

Fig. 6 is a plan view of the modified trip device shown in Fig. 5;

Fig. 7 is a detail sectional view taken substantially on line VII—VII of Fig. 5 and showing the latch for connecting and disconnecting the trip lever from its biasing means; and

Fig. 8 is a fragmentary detail view showing the method of adjustably securing the scale plate to the trip device.

Referring to Figure 1 of the drawings, the multipole circuit breaker mechanism is mounted on a base 11 of insulating material and a casing 13 may be provided to enclose the mechanism. The mechanism is supported on a frame structure 16 comprising a pair of substantially parallel side walls 17 (only one being shown) connected adjacent the base 11 by a cross member 18, secured to the center portion of the base 11 by means of bolts 21 and 23. The bolt 23 extends through the cross member 18 and serves to rigidly secure a connector 27 of conducting material to the cross member. The sides 17 are also joined by a cross member 25 at their outer ends to form a rigid framework for supporting the breaker mechanism.

A contact arm 30 for the center pole of the breaker is provided with a pair of spaced arms 31 pivotally mounted on a pivot comprising a shaft 29 extending through an opening in the connector 27 and mounted in openings in the sides of the frame 16. The arms 31 are disposed one on each side of the connector 27 and are pivoted on the ends of the shaft 29 which project beyond the sides of the connector and into openings in the sides of the frame 16.

The contact arm 30 pivotally carries a main contact member 47 pivotally mounted on a pivot 49 supported in projections 51 (only one being shown) of the contact arm 30. A contact 33 secured to the contact member 47 cooperates with a stationary contact 39 mounted on a conductor 41 secured to the base 11 by bolts 43. The conductor 41 is bent at right angles and extends through an opening in the base 11 to form a terminal connector 45.

An arcing contact member 55 is pivoted on a pivot pin 57 supported in projections 59 of the contact arm 30. The contact member 55 has secured thereto an arcing contact shoe 58 which cooperates with a stationary arcing contact 57 secured to an arcing horn 56, the arcing horn being secured to the conductor 41 by means of screws 58.

A spring 53 compressed between a spring seat on the contact member 47 and a spring seat on the contact arm 30 provides contact pressure for the contacts 33—39. Similarly a spring 63, surrounding a rod 61 pivotally connected to the arcing contact member 55, and compressed between a washer 65 on the rod and a spring seat on the

contact arm 30 provides contact pressure for the arcing contacts 55—57. The rod 61 extends through and is slideable in an opening in the upper end of the contact arm 30.

The circuit breaker is of the multipole type, each pole thereof being provided with a contact arm 30 (only one being shown). The contact arms 30 for the outer poles are not provided with arms 31 but are securely clamped on a tie bar 67 which is clamped to the contact arm 30 of the center pole by a clamp 70 and bolt 71, the poles being insulated from each other by a sheath of insulating material 69 between the tie bar 67 and the contact arms 30. All of the contact arms 30 of the breaker, therefore, operate as a unit to simultaneously operate the contacts for all of the poles of the breaker. The stationary main and arcing contacts and the movable main and arcing contacts of the two outer poles are of the same construction as the contact means of the center pole shown and described.

When the contact arm 30 is rotated in a clockwise direction (Fig. 1) to open the contacts, as will be described later, the springs 53 and 63 rock the contact members 47 and 55, respectively, counterclockwise about their pivot pins. This movement of each contact member 47 is limited by a projection 73 thereon striking the body of the contact arm 30. The counterclockwise movement of each contact member 55 is limited by a nut 75 on the end of the rod 61 striking the contact arm 30. The adjustment of the nut 75 on the rod 61 is such that the main contacts 33—39 open shortly before the arcing contacts 55—57 open.

The arc, resulting from the rupture of the circuit, is dissipated by an arc extinguisher 76 of which three are provided, one for each pole of the breaker. Each of the arc extinguishers comprises, generally, a stack of slotted plates disposed adjacent the path of travel of the arcing contact 55. These plates cause the arc to be drawn in a direction towards the ends of the slots which results in breaking up the arc into a number of small arcs and causes said arcs to be quickly cooled and extinguished.

The electrical circuits for the several poles of the breaker are substantially the same, each circuit extending from the terminal 45 through the contact member 41, the stationary main contact 39, the movable main contact 33, the contact member 47, a flexible shunt conductor 79 connecting the contact member 47 to the connector 27, a terminal 72 secured to the connector 27 by bolts 74, a conductor 78 having its one end secured to the terminal 72 and its other end secured to a conductor 81. The conductor 81 is bent at substantially right angles and projects through an opening in the base 11 where it forms a terminal 83 which, together with the terminal 45, serves to connect the breaker in an electrical circuit.

The circuit for the arcing contacts extends from the conductor 41 through the contacts 33 and 55, the arcing contact member 55, a flexible shunt conductor 77 to the main contact member 47 and thence over the circuit previously described to the terminal 83.

The contact arm 30 is biased in a clockwise direction toward open position by a pair of springs 85 having one end connected to the contact arm 30 near its free end, and the other end hooked to a fixed pivot pin 87 supported in the frame 16. Under normal circuit conditions, the contact arm 30 is releasably re-

strained in closed circuit position (Fig. 1) by means of a linkage and toggle arrangement forming the operating mechanism described as follows:

A lever 89 comprising a pair of parallel levers joined by an integral cross member 117 is pivotally mounted on a fixed pivot 91 supported in the frame 16. The lever 89 is connected to the arms 31 of the contact arm 30 by means of a main operating toggle comprising toggle links 93 and 95. The toggle link 95 comprises a pair of links (only one being shown) joined by a cross member 115 and is connected to the arms 31 by a pivot pin 99. The toggle links 93 and 95 are pivotally connected by a knee pivot pin 97 and the link 93 is pivotally connected to the lever 89 by a pin 101. A link 103 connects the free end of the lever 89 to one end of a lever 105 pivoted on the fixed pivot 81. The other arm of the lever 105 is pivotally connected to one end of a toggle link 107 which has its opposite end pivotally connected to a toggle link 109 by a knee pin 111, the toggle link 109 being pivoted on a fixed pivot 113 supported in the frame 16. The toggle link 107 comprises a pair of links joined by a yoke 119 having a bent out portion 121, the purpose of which is to cooperate with manually operable means to trip the breaker as will be later described. The toggle link 109 comprises a pair of links joined at their ends adjacent the pivot 113 by a yoke 123 having formed portions 125 and 127 thereon.

The linkage just described serves to releasably hold the contact arm and consequently the contacts in closed position. When the contact arm 30 is in the closed contact position, the main operating toggle 93-95 is overcenter above a line through the centers of the pins 99 and 101, and the toggle comprising the link 93 and the lever 89 is overcenter above a line through the center of the knee pin 97 and the fixed pivot 91. The overcenter movement of the toggles 93-95 and 93-89 is limited by a projection 126 on the link 93 striking the cross member 115 joining the links 95. In this position, the lever 89 is biased in a clockwise direction by the springs 85 but is prevented from rotation by the tripping toggle 107-109 being biased overcenter to the left of a line through the fixed pivot 113 and the point of connection of the toggle link 107 and the lever 105 by a spring 128, tensioned between the yoke 119 and the fixed pivot 113. The overcenter position of the toggle 107-109 is adjustably limited by the formed portion 125 of the yoke 123 striking an adjusting screw 129 in the cross member 25 of the frame 16.

It can be seen that the force exerted by the springs 85 on the contact arm 30 is transmitted through the linkage just described and applied to the tripping toggle 107-109 which, in its overcenter position (Fig. 1), is effective to hold the contacts in closed position. The tripping toggle 107-109 is adapted to be moved overcenter in an outward direction to collapsed position to cause opening of the contacts, by a trip device indicated generally at 133 (Figs. 1, 2, 3 and 4) which acts through a trip rod 135.

The trip rod 135 is slidably supported in a shunt trip electromagnet coil enclosed in a casting 138 secured to the frame 16. The coil is adapted to be energized by a shunt circuit (not shown) or by a manually controlled switch to operate the trip rod 135 from a distance in a manner well known in the art.

The trip device 133, when operated in response to overload current, is adapted to thrust the rod 135 upwardly, in a manner to be described later. When the trip rod 135 is thrust upwardly, the upper end thereof strikes the formed portion 127 on the yoke 123 and rocks the tripping toggle link 109 clockwise (Fig. 1) about its pivot 113 moving the tripping toggle 107-109 overcenter in a direction to cause its collapse.

When the tripping toggle 107-109 moves overcenter, it permits the springs 85, acting through the contact arm 30 and the main operating toggle 93-95 to rock the lever 89 clockwise about its pivot, which movement is transmitted through the agency of the link 103 to rock the lever 105 clockwise and complete the collapse of the tripping toggle 107-109. The main operating toggle 93-95 does not immediately break overcenter but travels as a unitary linkage with the contact arm 30 and the lever 89 until the movement of the contact arm 30 is arrested by the arm striking a stop portion 137 of the frame structure 16. When this occurs the inertia of the toggle link 95, including the comparatively heavy cross member 115, is such that the toggle 93-95 is forced overcenter in a direction to cause its collapse. By the time the knee pin 97 of the main toggle has passed below the center line 99-101, the weight of the linkage and parts causes the main toggle to collapse and causes the lever 89, the link 103, lever 105 and the tripping toggle 107-109 to be automatically reset to their normal positions as shown in Fig. 1.

When the main toggle 93-95 has collapsed, the force of the springs 85 is no longer applied to the tripping toggle 107-109 and the spring 128 assists the weight of the parts in immediately restoring the latter toggle to its overcenter position and in restoring the lever 105, link 103 and lever 89 to their normal positions. The main toggle 93-95 remains in collapsed condition until the contacts are reclosed which may be effected either automatically or manually.

In order to close the contacts manually, an operating handle 141 is provided. This handle is rotatably mounted in a frame 143 of insulating material secured to the main frame structure 16. A link 151, adapted to be thrust downwardly (Fig. 1) by a crank arm (not shown) on the handle shaft upon clockwise or closing movement of the handle 141, is notched at its lower end and engages an hour glass-shaped roller 153 mounted for rotation on a cross member 147 forming the outer end of a contact closing lever 145. The lever 145 comprises a pair of substantially parallel spaced levers 145 pivotally mounted on the fixed pivot 91 and rigidly joined at their outer ends by the cross member 147 which carries the roller 153. The other ends of the levers 145 are rigidly connected by a cross bar 149. Projections 152 on the cross bar 149 support a pivot 157 upon which is rotatably mounted a roller 155. The levers 145 straddle the frame 16.

Downward movement of the link 151 rocks the contact closing lever 145 clockwise about its pivot 91 during which movement the roller 155 engages the collapsed main toggle 93-95 and moves this toggle to its overcenter position. Straightening the toggle 93-95 rotates the contact arm 30 counterclockwise to close the contacts and tension the springs 85, since the pivot 101 of the operating toggle is held in fixed position by the linkage 103, 105, 107 and 109.

After the contacts are closed the handle 141 is released whereupon a spring 158, tensioned between the frame 16 and the contact closing lever 145 rocks the lever counterclockwise to its normal position. This movement thrusts the link 151 upwardly and returns the operating handle 141 to its neutral position.

The contacts may be closed electrically by means of a motor 139 mounted on a support frame 140 secured to the main frame 16 by an insulating plate 142. The motor may be energized from any suitable source and in a manner well known in the art. When energized, the motor is adapted, through a suitable reduction gearing, to rotate a crank disc 130 which carries an anti-friction roller 131. The roller strikes a curved face 132 on an arm 134 secured to the side of the contact closing lever 145 and rocks the lever clockwise to close the contacts in the previously described manner. As soon as the roller 131 passes out of engagement with the arm 134, the spring 158 acts to restore the contact closing lever 145 to its normal position (Fig. 1). The motor 139 is deenergized by a suitable limit switch (not shown).

The breaker may also be tripped open manually by proper manipulation of the handle 141. When the handle is rotated in a counterclockwise or tripping direction, a projection (not shown) on the thrust link 151 engages the previously described projection 121 on the yoke 119 of the tripping toggle link 107 and moves the tripping toggle 107-109 overcenter in a direction to cause its collapse. This causes opening of the contacts in the manner previously set forth.

As was stated previously, the trip rod 135 is thrust upwardly to trip the breaker by operation of the trip device 133 in response to overload conditions in the circuit controlled by the breaker. A plurality of trip devices 133 is provided one for each pole of the breaker. It is to be understood, however, that a trip device may be provided for at least two of the poles of the breaker and will function in the same manner to trip the breaker. Since the trip devices are alike, only one will be described.

Each of the trip devices 133 (Figs. 1, 2, 3 and 4) includes a laminated U-shaped magnet core 161 and a frame comprising spaced parallel members 163 joined by a cross member 165. The ends of the frame member 163 adjacent the magnet core 161 are bent at right angles to form mounting feet 167 abutting against the core 161, and bolts 169 pass through openings in the feet 167, the core 161 and the base 11 to rigidly secure the frame 163 and the core 161 to the base. A spacer 171 of insulating material is provided between the magnet core 161 and the base 11.

A trip lever comprising a pair of spaced parallel levers 173 is pivotally supported on a pivot pin 175 mounted in the frame members 163. The levers 173 are rigidly connected at their outer ends by a cross member 177, and a laminated armature 179 is secured to the opposite ends of the levers so as to cooperate with the magnet core 161. The magnetic air gap is adjustably determined by a screw 188 in the cross member 165 of the frame 163, the screw serving to limit the clockwise movement of the trip lever 173.

Each of the cross members 177 has an adjusting screw 181 mounted thereon and a lock nut 183 is provided to lock the screw in its adjusted position.

Upon operation of the trip lever 173 in response to an overload current in the circuit of its corre-

sponding pole, the screw 181 strikes a corresponding arm 185 fixed on a trip bar 187 rotatably mounted in a bracket 189 secured to the casing 188, and rocks said trip bar in a clockwise direction. The trip bar 187 extends across all of the poles of the breaker and an arm 185 is provided for each pole. One of the arms 185 is in alignment with the trip rod 135 and, upon clockwise movement of the trip bar 187, the rod 135 is thrust upwardly to trip the breaker in the manner previously described.

The trip lever 173 is biased against operation by the magnet core by a spring 191 tensioned between the cross member 177 and a spring anchor 193 in a formed projection 195 of the cross member 165 of the frame 163.

A lever comprising a pair of spaced arms 197 (Figs. 2, 3 and 4) is pivotally mounted on the pivot pin 175. These arms 197 are rigidly connected by pivot pins 205 and 207. A latch 209 pivotally supported on the pin 205 is provided with a shoulder 211 and is biased by a spring 215 into engagement with a latch member 213 secured to the cross member 177 of the trip lever.

A link comprising a pair of spaced arms 217 disposed one on each side of the latch 209, is pivoted on the pin 207. The arms 217 are rigidly connected by a yoke 219 which is provided with an extension 221. A pin 223 fixed in the latch 209 projects through elongated slots 225 (Figs. 3 and 4) in the arms 217 to operatively connect the link to the latch 209.

A bimetal element 227 is disposed along the upper side of the heater portion of the conductor 78 and both the bimetal element and the heater portion of the conductor 78 are securely fastened to a bracket 229 by rivets 231 (Fig. 3). The bracket 229 extends between the side members of the frame 163 and is suitably secured thereto.

An adjusting bimetal element 233 is provided with ears 235 which are pivotally supported on a pin 237 mounted in the depending ends of a bracket 239 secured to the under side of the cross member 165 of the frame 163. A spring 241 has one of its ends hooked in a spring anchor 243 of insulating material secured to the current responsive bimetal 227 at a point near its free end. The other end of the spring 241 is connected to a spring anchor 245 of insulating material secured to the left hand end (Figs. 3 and 4) of the bimetal 233. The spring 241 passes through an opening in the cross member 165 of the frame 163. The tension of the spring 241 holds the right hand end (Fig. 3) of the pivoted bimetal element 233 in contact with the tip of an adjusting screw 247 mounted in the formed portion 195 of the cross member 165.

One of the arms of the lever 173 is provided with an extension 251 to the end of which is attached one end of a biasing spring 253 having its other end attached to a movable plate 255. An adjusting screw 257 (see Fig. 8) which passes through an opening in the formed portion 195 of the cross member 165, cooperates with the plate 255 and serves to move the plate up and down, depending on the direction of rotation of the screw, for the purpose of adjusting the tension of the spring 253.

When the shoulder 211 of the latch 209 (Figs. 1 and 4) is in engagement with the latch member 213, the spring 253 is effective to bias the trip lever 173 against tripping movement.

The movable parts of the trip device are shown in Fig. 1 in the positions they assume under nor-

mal circuit conditions. Current of rated value flowing through the circuit of any pole of the breaker and, therefore, through the heater portion of the conductor 18 and through the conductor 81 which passes between the legs of the magnet core 161, causes but slight energization of the magnet. The pull of the magnet under normal conditions is not sufficient to overcome the combined force of the two springs 191 and 253. Also normal current flow through the heater element 18 does not heat the bimetal element 227 sufficiently to cause it to flex from its normal shape.

Upon the occurrence of a continuous overload below a predetermined value, for instance, below approximately 1000 percent of normal, the bimetal element 227 is heated by the overload current and when heated a predetermined amount it flexes in an upward direction. When the bimetal flexes in response to an overload current, an adjusting screw 249, secured by a lock nut at a point near the free end of the bimetal 227, engages the extension 221 of the trip member 217 and rocks the link clockwise about its pivot 207. This movement of the trip member, due to the pin and slot connection 223-225 rocks the latch 209 counterclockwise and unlatches the trip lever 173 from the spring biased lever 197. Since the biasing effect of the spring 253 is no longer applied to the trip lever 173, the electromagnet 161 now overcomes the tension of the light spring 191 and operates the trip lever 173 to trip the breaker in the previously described manner. The force exerted by the electromagnet at or slightly below normal rated current is sufficient to move the trip lever 173 to tripping position against the tension of the spring 191 to trip the breaker when the latch 209 is released.

As soon as the flow of current is interrupted by opening of the contacts and the electromagnet is deenergized, the spring 191 acts to restore the trip lever 173 to its normal position (Fig. 1), and, as the bimetal element cools and resume its normal shape, the spring 215 rocks the latch 209 clockwise to reengage the shoulder 211 with the latch 213 of the trip lever 173.

The bimetal element due to the time it takes to be heated a sufficient amount to flex, thereby provides a desirable time delay during which the abnormal current may return to normal without causing circuit interruption.

The trip device is constructed to instantaneously trip the circuit breaker upon the occurrence of an overload above the predetermined value, that is, 1000 percent or more of normal current, or a short circuit. This value is, of course, variable by the adjusting screw 251. In this event the breaker is tripped and the current ruptured before the bimetal element is heated an appreciable amount and, therefore, the latch 209 is not operated to disconnect the spring 253 from the trip lever 173. The magnetic energy on such overloads is sufficient to overcome the combined force of both the springs 191 and 253 and trip the breaker. Since the latch 209 remains latched to the trip lever 173, the counterclockwise or tripping movement of the lever 173 rocks the spring biased lever 197 about the pivot 175, the spring 215 acting to maintain the latch 209 in engagement with the latch member 213 on the lever 173. During this action, the pin and slot connection 223-225 permits relative movement of the link 217 and

the latch 209. The parts are shown in their instantaneously tripped position in Fig. 4. The springs 191 and 253 restore the parts to normal unstripped positions when the circuit is interrupted.

The movable plate 255 (Figs. 3, 4 and 8), to which the spring 253 is attached, is provided with a pointer 259 which projects through a guide slot 281 in a scale plate 283. This scale plate is adjustably mounted on spaced extensions 285 integral with the formed projection 195 of the cross member 165, by means of screws 287 (Fig. 8) in the extensions and slots 288 in the sides of the scale plate. The scale plate 283 bears a scale (not shown) which indicates the instantaneous tripping point of the breaker. Obviously rotating the screw 287 will move the plate 255 up or down and vary the tension of the spring 253 according to the direction the screw is turned. Varying the tension of the spring 253 varies the instantaneous tripping point of the breaker, and the pointer 259 which moves with the plate 255 indicates the percentage of overload current at which the breaker will trip.

The pivoted bimetal element 233 (Figs. 1, 3 and 4) serves to manually adjust the tension of the spring 241. Turning the screw 247 causes the bimetal 233 to rotate either clockwise to decrease the tension of the spring or counterclockwise to increase the tension according to the direction the screw is turned. Varying the tension of the spring 241 varies the minimum overload tripping current at which the bimetal element will flex when heated to release the latch and cause tripping of the breaker.

The bimetal element 233 serves the additional purpose of automatically varying the tension of the spring 241 according to variation in air temperature. The bimetal 233 is disposed to flex downwardly in response to an increasing ambient temperature thus varying the tension of the spring 241 and counteracting the effect of the ambient temperature on the bimetal element 227.

Figs. 5, 6 and 7 illustrate a modified embodiment of the invention in which the bimetal element acts directly on the latch to disconnect the trip lever from its biasing spring. Certain of the parts in the illustrative embodiment of the modification are the same as corresponding parts in the previously described embodiment and have been given the same reference characters.

Referring to Fig. 5, a U-shaped bimetal element 271 is rigidly and electrically secured to a shunt conductor 273 which is secured to the end of terminal conductor 83. Adjacent the upper leg of the bimetal 271, the shunt conductor 273 is electrically secured to a conductor 275 which extends upwardly and may be secured to the connector 27 (Fig. 1) in a suitable manner. Pivotally mounted on the pivot pin 175 is a lever 276 comprising a pair of parallel arms 277 and 278 rigidly connected near the pivot 175 by a yoke 281. The arms 277 and 278 extend downwardly and are bent towards each other (see Fig. 6), the arm 277 extending toward the right (Fig. 5) a greater distance than the arm 278. The arm 278 is bent at right angles toward the arm 277 as at 283 (Fig. 6) and is then bent back parallel to and adjacent to the arm 277 at 285, the portion 285 being secured to the arm 277. A spring 287 has its upper end connected to a spring anchor 289 on the free end of the arm 277 and its lower end connected to an anchor 291 secured to a movable plate 293. An adjusting screw 295 supported in the extension 195 of the frame 163

is rotatably connected to the plate 293 in such a manner that rotation of the screw 295 shifts the plate 293 up or down, depending on the direction the screw 295 is rotated, to vary the tension of the spring 287 and consequently the instantaneous tripping characteristic. The spring 287 biases the lever 276 in a clockwise direction against the cross member 165 of the frame 163.

Referring to Fig. 7, a latch 297 pivoted on a pivot pin 298 supported on the bent portion 293 of the arm 278, is biased by a leaf spring 301 into latching engagement with a latch member 303 secured to the under face of the cross member 177 of the trip lever 173. It can thus be seen that the spring biased lever 276 is operatively connected to the trip lever 173 and that therefore, the spring 287 is normally effective to bias the trip lever 173 against the attraction of the electromagnet 161.

The free end of the bimetal element 271 carries an adjusting screw 305, the end of which projects inwardly and is adapted, when the bimetal element is heated a predetermined amount in response to an overload, to engage the latch 297 and rock the latch clockwise (Fig. 7) to disconnect the trip lever 173 from the influence of the spring 287. When the lever 173 is freed from the tension of the spring 287, the pull of the electromagnet 161 is sufficient to overcome the tension of a light spring 307, tensioned between a projection on the armature 179 and a projection 309 on the base 11, and to operate the trip lever 173 to trip the breaker.

As in the original embodiment the force exerted by the electromagnet at or slightly below normal rated current is sufficient to move the trip lever 173 to tripping position against the tension of the spring 307 to trip the breaker if the latch 297 is released.

The spring 307 rocks the trip lever 173 clockwise to normal position when the breaker opens and the electromagnet 161 is deenergized. The spring 301 reengages the latch 297 with the latch member 303 when the bimetal has cooled and resumed its normal position.

Upon the occurrence of an overload above the predetermined value or a short circuit, the bimetal 271 does not have time to become heated a sufficient amount to cause unlatching of the trip lever 173 from the spring-biased lever 276. The pull of the electromagnet is great enough however to overcome the combined force of the springs 287 and 307 and cause instantaneous tripping of the breaker. Since the latch 297 remains effective the lever 276 is rocked counterclockwise against the tension of the spring 287. Upon deenergization of the electromagnet the spring 287 rocks the lever 276 clockwise and, due to the latch connection 297-303, rocks the trip lever 173 clockwise to normal position aided by the spring 307.

The minimum tripping point of breaker under the control of the bimetal 271 may be varied by adjustment of the screw 305, and the instantaneous tripping point of the modified trip device may be varied by adjustment of the screw 295. A pointer 311 (Fig. 5) is provided on the movable plate 293 which pointer cooperates with the scale plate 263 to indicate the percentage of overload current at which the breaker will be tripped instantaneously.

The breaker is trip free under all conditions, that is the contacts will be automatically opened if the handle 141 is held in the closed position against an overload current or if an attempt

should be made to close the contacts against an overload.

It can be readily seen that the toggle and linkage structure of the operating mechanism acts to reduce the tripping load to a minimum, the load on the tripping toggle 167-168 being such that a very small force is required to trip the breaker. This is made possible by omitting latch mechanism from the operating mechanism.

The parts of the trip device are constructed to cooperate with the operating mechanism to further reduce the tripping effort required of the bimetal element. It will be noted that the bimetal does not directly trip the breaker but serves, when heated a predetermined amount to disconnect at least a part of the biasing means from the trip member so that the latter may operate to more quickly trip the breaker. The operating characteristic of the bimetal element is varied to compensate for ambient temperature by the use of a thermal element resiliently connected to the bimetal element and the thermal element is provided with a manual adjustment. The trip device forms a unitary structure which may be easily removed from the breaker so that another trip device may be substituted.

Having described several embodiments of the invention in accordance with the patent statutes, it is to be understood that various changes and modifications may be made in the structural details disclosed without departing from some of the essential features of the invention. It is, therefore, desired that the appended claims be given as reasonably broad interpretation as the prior art permits.

I claim as my invention:

1. In a circuit breaker, a switch member biased to open position, operating mechanism for said switch member comprising an operating toggle connected to the switch member, a linkage connected to the toggle for holding one end of the toggle in operative position, said linkage constituting the sole means for holding said end of the toggle in operative position, and a trip device comprising a member operable to move the linkage to effect an opening operation of the switch member, a plurality of biasing means opposing operation of said member, and a bimetal element fixedly secured at one portion thereof to a fixed support and operable in response to overload currents to disconnect one of said biasing means from the trip member.

2. In a circuit breaker, a switch member biased to open position, operating mechanism for said switch member comprising an operating toggle connected to the switch member, a load reducing linkage connected to one end of the toggle said linkage comprising the sole means for holding said one end of said toggle in operative position, and a trip device operable to move the linkage to cause opening operation of the switch member, said trip device comprising a trip lever, biasing means opposing operation of said trip lever, a pivoted connection for releasably connecting a part of said biasing means to said trip lever, electromagnetic means responsive to overloads for operating the trip lever, and thermally responsive means operable when heated a predetermined amount for operating said connection to disconnect at least a part of the biasing means from the trip lever.

3. In a circuit breaker having a switch member biased to open circuit position, operating mechanism therefor comprising an operating toggle connected to said switch member, a link-

age for holding one end of the toggle in operative position, and a trip device operable to move said linkage to cause an opening operation of the switch member, said trip device comprising a trip lever operable to move said linkage, means biasing said trip member against operation at least a part of said biasing means being releasably connected to said trip member, and a bimetal element fixedly secured at one portion to a fixed support and operable when heated a predetermined amount in response to overload currents to disconnect the releasable part of the biasing means from the trip member.

4. In a circuit breaker, a switch member biased to open position, operating mechanism for said switch member including an operating toggle connected to the switch member, a linkage connected to one end of said toggle for holding said toggle in operative position, and a trip device operable to move said linkage to effect an opening operation of the switch member, said trip device comprising a trip lever, an electro-magnet operable in response to overload currents above a predetermined value to operate the trip lever, means biasing said trip lever against operation, a pivoted latch for releasably connecting a part of said biasing means to said lever, and a bimetal element operable when heated a predetermined amount to operate said latch and disconnect the releasable portion of the biasing means from the trip lever to permit said electro-magnet to operate the trip lever to trip the breaker in response to overloads below said predetermined value.

5. In a circuit breaker, a switch member biased to open position, operating mechanism for said switch member including an operating toggle connected to the switch member, a linkage connected to the toggle for holding one end of said toggle in operative position, and a trip device comprising a trip lever operable to move said linkage to cause opening operation of said switch member, electro-responsive means for operating the trip lever, a plurality of springs biasing said trip lever against operation, a latch for releasably connecting at least one of said springs to said trip lever, and a bimetal element operable when heated a predetermined amount for operating the latch, said latch being mounted for movement independently of said bimetal element.

6. In a circuit breaker, a switch member biased to open position, operating mechanism for said switch member, and a trip device comprising a lever operable to cause an opening operation of the switch member, means biasing said lever against operation, electro-magnetic means responsive to overload currents to operate said lever, a bimetal element responsive when heated a predetermined amount to render a part of the biasing means ineffective, and a member thermally responsive to ambient temperatures resiliently connected to said bimetal element.

7. In a circuit breaker, a switch member biased to open position, operating mechanism for said switch member, a trip device comprising a trip member operable to cause an opening operation of the switch member, means biasing said trip member against operation, electromagnetic means operable in response to overload currents to operate the trip member, a bimetal element responsive when heated a predetermined amount to render at least a part of the biasing means ineffective, a thermal member, and a spring connecting said thermal member to said bimetal element,

said thermal member being responsive to ambient changes in temperature to vary the tension of the spring and compensate for the effect of ambient temperature on the bimetal element.

8. In a circuit breaker, a switch member biased to open position, operating mechanism for said switch member, a trip device comprising a trip member operable to cause an opening operation of the switch member, means biasing said trip member against operation, an electro-magnet for operating the trip member in response to overload currents, a bimetal element operable when heated a predetermined amount to render at least a part of the biasing means ineffective to oppose operation of the trip member, a thermal member, a spring connecting said thermal member to the bimetal element, said thermal member being responsive to ambient temperatures to vary the tension of said spring, and means to manually adjust the thermal member to vary the tension of the spring.

9. In a circuit breaker, a switch member biased to open position, operating mechanism for said switch member comprising an operating toggle connected to said switch member, a linkage connected to the toggle for holding one end of said toggle in operative position, and a trip device comprising a lever operable to move said linkage to effect an opening movement of the switch member, a plurality of means biasing said lever against operation, one of said biasing means being adjustable to vary the tripping characteristic of the breaker, electromagnetic means responsive to overloads for operating the lever, and a thermally responsive element operable in response to overload currents below a predetermined value to disconnect the adjustable biasing means from the lever.

10. In a circuit breaker, a switch member biased to open position, operating mechanism for the switch member, a trip device comprising a trip member operable to cause an opening operation of the switch member, an electro-magnet for operating said trip member upon the occurrence of an overload above a predetermined value, means biasing the trip member against operation, a latch member connecting the biasing means to said trip member, a current responsive bimetal element responsive when heated a predetermined amount to disconnect the trip member from the biasing means, a pivoted thermal member, a spring tensioned between the thermal member and the bimetal element, said thermal member being responsive to ambient temperatures to vary the tension of said spring, and manually operable means to rotatably adjust said thermal member.

11. In a circuit breaker, relatively movable contacts, a switch member for opening and closing said contacts, said switch member being biased to open position, operating mechanism for said switch member, a trip device comprising an electromagnet, a member operable by said electro-magnet for causing an opening operation of the switch member, means for biasing said member against operation, a pivoted latch member for at times disconnecting the member from said biasing means, and a bimetal element mounted on a fixed support and operable in response to overload currents to move the latch to disconnect the member from the biasing means, said bimetal element constituting the sole means for operating said latch.

12. In a circuit breaker, a switch member biased to open position, operating mechanism for

said switch member including a linkage operable to cause opening of the circuit, a trip device comprising a trip member, an electro-magnet for operating said trip member in response to overload currents, means for biasing said trip member against operation, pivoted means operable at times to disconnect the trip member from the biasing means, and a bimetal element operable when heated a predetermined amount in response to overload currents below a predetermined value to operate said pivoted disconnecting means, said bimetal element constituting the sole means for operating the disconnecting means.

13. In a circuit breaker, a switch arm biased to open position, operating mechanism for said switch member including an operating toggle connected to said switch member, a load reducing linkage connected to said toggle for holding one end of said toggle in operative position, a trip device comprising a trip member operable to move the linkage to effect opening of the circuit, means biasing said trip member against operation, electro-magnetic means operable in response to overload currents to actuate the trip member, and a bimetal element mounted on a fixed support and operable in response to overloads below a predetermined value to disconnect the trip member from the biasing means, said electro-magnet being operable in response to overloads above said predetermined value to actuate the trip member without disconnecting trip member from the biasing means.

14. In a circuit breaker, a switch arm biased to open position, operating mechanism for said switch arm including a linkage movable to cause opening of the circuit, a trip device comprising a trip member operable to move said linkage, an electro-magnet for actuating the trip member in response to overload currents, an arm biased against operation, a latch pivotally supported on said arm and normally latching said arm to the trip member, a lever pivotally supported on said arm, said lever being operable to unlatch the trip member, and a bimetal element operable when heated a predetermined amount in response to overload currents for actuating said lever.

15. In a circuit breaker, relatively movable contacts, operating mechanism including a linkage operable to cause opening of the contacts, a trip device operable in response to overload currents to actuate the linkage, said trip device comprising a trip member, an arm biased by a spring against operation, a latch pivotally supported on said arm operatively connecting said arm and the trip member, a lever pivotally supported on the arm and operatively connected to said latch, a bimetal element operable when heated a predetermined amount in response to overload currents to actuate said lever and unlatch the spring biased arm from the trip member.

16. In a circuit breaker, a switch member operable to open and close the circuit, operating mechanism therefor, a trip device comprising a trip member operable to cause an opening operation of the switch member, a bimetal element operable when heated a predetermined amount in response to overload currents to cause operation of the trip member, a thermal element, resilient means having one end attached to the bimetal element and having the other end attached to the thermal element and stretched therebetween, said thermal element being responsive to ambient changes in temperature to vary the tension of the resilient means to com-

penate for the effect of ambient temperatures on the bimetal element, and means cooperating with said thermal element at a point spaced from the point of attachment of said resilient means to manually vary the tension of the resilient means.

17. In a circuit breaker, a switch member operable to open and close the circuit, operating mechanism for said switch member, a trip device including a trip member operable to cause an opening operation of the switch member, a bimetal element operable in response to overload currents to effect operation of the trip member, a spring connected to said bimetal element, and manual means separate from said bimetal element and operable to vary the tension of said spring to thereby vary the operating characteristic of said bimetal element.

18. In a circuit breaker, a switch member biased to open position, operating mechanism for said switch member, a trip device including a trip member operable to cause an opening operation of the switch member, biasing means opposing operation of the trip member, a bimetal element operable in response to overload currents to disconnect said biasing means from the trip member, and resilient means connected to the bimetal and adjustable to vary the operating characteristic of the bimetal.

19. In a circuit breaker, a switch member biased to open position, operating mechanism therefor including an operating toggle connected to the switch member, said operating mechanism including means for moving the switch member to closed position, a linkage for holding one end of the operating toggle in operative position, said linkage including a tripping toggle and constituting the sole means for holding the operating toggle in operative position, a trip device including a trip member operable to move said tripping toggle to effect an opening operation of the switch member irrespective of the position of the closing means, a plurality of biasing means opposing operation of the trip member, at least one of the biasing means being releasably connected to said trip member, means for adjusting the releasable biasing means to vary the tripping characteristic of the device and a bimetal element operable when heated a predetermined amount in response to overload currents to disconnect the releasable biasing means from the trip member.

20. In a circuit breaker, a switch member biased to open circuit position, operating mechanism therefor including a toggle connected to said switch member, a linkage including tripping toggle, said toggle comprising the sole means for holding the operating toggle in operative position, a trip device operable to move said linkage to cause an opening operation of the switch member, said trip device comprising a trip member operable to actuate the tripping toggle, biasing means opposing operation of said trip member, at least a part of said biasing means being releasably connected to said trip member, manual means for adjusting the releasable biasing means to vary the tripping characteristic of the device and a bimetal element operable when heated a predetermined amount in response to overload currents to disconnect the releasable biasing means from the trip member.

21. In a circuit breaker, a switch member, operating mechanism for said switch member, a trip device comprising a trip member operable to cause an opening operation of the switch mem-

ber, biasing means opposing operation of the trip member, a bimetal element operable in response to overload current below a predetermined value for disconnecting the trip member from the biasing means, an armature on the trip member, an electro-magnet core responsive to overload currents for attracting the armature to operate the trip member, and a rigidly mounted energizing conductor for the electro-magnet, said bimetal element being secured to said conductor and at least a portion of said bimetal element being disposed in intimate contact with the energizing conductor, said electromagnet being operable at times to operate the trip member without said biasing means being disconnected from said trip member.

22. In a circuit breaker, a switch member biased to open position, operating mechanism for said switch member, a trip device including a trip member, biasing means opposing operation of the trip member, an armature on said trip member, an electro-magnetic core for operating the armature to cause an opening operation of the switch member, a fixedly mounted energizing conductor for said magnet core, a non-current carrying bimetal element secured to said conductor and having at least a portion disposed in intimate contact with said conductor and operable when heated a predetermined amount in response to overload currents to disconnect the trip member from the biasing means, said elec-

tromagnet at times operating said trip member irrespective of the connected condition of said biasing means said trip device comprising a unitary structure removably mounted on the circuit breaker.

23. A trip device for a circuit breaker comprising a trip member operable to cause opening of said breaker, means biasing said trip member against operation, current responsive means operable when heated a predetermined amount in response to overload currents to disconnect said trip member from the biasing means, a thermal element, resilient means connecting said current responsive means to said thermal element, said thermal element being operable in response to changes in ambient temperature to vary the tension of said resilient means to compensate the current responsive means for the influence of ambient temperatures, and means to manually vary the tension of said resilient means.

24. A trip device for a circuit breaker comprising a trip member operable to effect opening of said breaker, biasing means opposing operation of the trip member, an electro-responsive element operable in response to overload currents to disconnect said biasing means from the trip member, and resilient means connected to said electroresponsive element and adjustable to vary the operating characteristic of the electro- responsive element.

JOHN W. MAY.
